UNITED STATES PATENT OFFICE.

LEWIS T. HOUGHTON, OF WORCESTER, MASSACHUSETTS.

YARN GUIDE FOR WINDING MACHINES.

Application filed November 6, 1924. Serial No. 748,278.

To all whom it may concern:

Be it known that I, LEWIS T. HOUGHTON, a citizen of the United States, residing at Worcester, in the county of Worcester and

5 State of Massachusetts, have invented a new and useful Yarn Guide for Winding Machines, of which the following is a specification.

This invention relates to a device for guiding thread or yarn to a package on which it is to be wound and is particularly adapted for use on machines building up a tube or package having ends at right angles to the length thereof so as not to require any support at the end. In winding these tubes or packages it is necessary that the guide move along the same in contact with the yarn that has been laid on the package and it has been the practice heretofore to provide an eye 20 having a V-shaped groove which engages the package at the point at which the yarn passes to the package over a metallic surface. Ordinarily the yarn approaches the package at substantially a right angle to the surface of the package, that is radially, and makes a sharp angle or bend at this point which raises the fibers on the yarn as it passes over an angle and therefore produces roughness. These fibers once raised are not 25 laid back on the yarn in the winding of the tube and therefore the product is not as smooth as it might be.

Another disadvantage of the old type of guide eye is that as the yarn passes over the metallic surface at the point at which it is located on the package it wears a groove in the eye and this groove destroys the usefulness of the eye in a very short time, although they are hardened and every precaution is taken to reduce the wear.

The principal objects of this invention are to provide a construction of yarn guide which will avoid the wear of the yarn on the surface of the guide that engages or 45 supports the package and to provide means whereby the yarn will not form any acute angle or, in fact, any material angle as it passes to the surface of the yarn package.

The first object is accomplished by providing a guide which has no bottom surface in contact with which the yarn can pass to the yarn package but instead has a groove in which it is retained by the sides of the guide and which has no bottom. The second object is also accomplished by this construction as it permits the yarn to come

against the yarn package almost on a tangent line and therefore does not cause the fibers of the yarn to be raised on the convex side as it passes to the package. Another 60 object of the invention is to provide a detachable plate on the guide holder where it rubs across the traverse frame so that it can be replaced when worn without necessitating any wear on the holder itself. 65

Other objects and advantages of the invention will appear hereinafter.

Reference is to be had to the accompanying drawings, in which

Fig. 1 is an end view of the traverse mechanism and tube support for a winding machine with a holder and yarn guide constructed in accordance with this invention; 70

Fig. 2 is a front elevation of the same;

Fig. 3 is a view of the yarn guide taken 75 from the opposite side from that shown in Fig. 1; and

Fig. 4 is a sectional view on the line 4—4 of Fig. 3.

I have shown the invention as applied to 80 the usual traversing mechanism which moves the thread or yarn back and forth while winding it on a rotary tube T or the like to form the thread or yarn package P. I have shown the usual traverse rod 10 at 85 the bottom of the traverse frame 11. The holder 12 is fixed to the rod by a screw 13. These parts are shown as of the usual construction. I have shown the holder as provided with a detachable plate 15 formed of 90 sheet metal and having two side flanges 16 for engaging the sides of the holder and keeping it in position. It is also provided with two parallel projections 17 which pass through perforations 18 in the holder to secure it in position. This easily replaceable plate slides along the traverse frame 11 and receives the wear which otherwise would 95 wear out the holder and necessitate its replacement. 100

At the top the holder 12 which is formed of sheet metal is bent around at right angles to its plane to provide a supporting and locating flange 20, as shown in Fig. 3. This flange being integral with the holder constitutes a means for locating the yarn guide. This yarn guide comprises a sheet metal plate 21 having a flange 22 around three sides abutting against the edges of the flange 20 so as to constitute a 105 locating means.

The plate 21 is provided with a pair of

studs 23 and 24. The stud 23 is provided with a reduced screw threaded portion having a shoulder abutting against the rear of the plate 21 as it appears in Fig. 3 and 5 with a nut 25 thereon to secure it in position. This stud is comparatively short. The other stud is constructed in the same way and held firmly on the plate. These 10 constitute guides for the yarn and are located so that the stud 23 which is the final guide over which the yarn passes to the package P is located as near it as is convenient. It is passed through a plate 26 on the other side as shown in Fig. 1 15 which is shaped so that the other stud 24 will not pass through it necessarily.

The two plates 21 and 26 are held together and secured to the flange 20 by a screw or bolt 27. This with the stud 23 fixes 20 these three flanges or plates 20, 21 and 26 together. The latter are spaced apart by a washer 28 on the bolt or screw 27. This washer is large enough so that they are 25 spaced apart equally throughout their adjacent flat surfaces. I have shown the plate 26 as having a flange 29 around the edge. These flanges 22 and 29 are rounded out away from each other so as to form converging convex surfaces between which the 30 yarn can be drawn easily and thus permit of the threading of the device without any trouble.

In the operation of the guide the yarn 35 passes, if it comes from above, under the pin or stud 24 and then over the stud 23. From there it passes freely to the package, no matter how large it may be, on a tangent line. In other words, as the yarn package grows in size the two flanges 22 and 29 bear 40 against it all the time and the holder 12 moves out as the package grows and yet the yarn always comes to the package on a tangent. This is an important point because as the yarn is laid on the package, it is 45 moving in a straight path and therefore the fibers are not roughened up on its surface just at that point as they have been heretofore. This results in a very much smoother product than has been obtained before and 50 enhances its value materially. In the old form with which I am familiar the yarn usually is deflected so that it passes to the package radially or nearly so. My object is to prevent or reduce this deflection so that 55 the yarn goes to the package at an acute angle or tangent. Another point to be observed is that the yarn bears against no metallic surface after it leaves the stud 23. Where it is pressed against the yarn pack- 60 age there is no metallic surface behind it and therefore there is no surface at that point to be worn by the passage of the yarn over it and the pressure of the yarn against it or between it and the package. The yarn 65 is entirely free from metallic surfaces at the

point where it is wound on the package. Nevertheless the two plates 21 and 26 retain it in position between them no matter what its angle and keep it from moving side- 70 wise.

If there is a little wear on the convex surfaces of the flanges 22 and 29 that wear from the top down so that the wear is uniform along these surfaces and tends to keep them smooth instead of grooving them, but there is very little wear upon them because they do not press the thread against the package. Of course the wear on the stud 23 cannot be avoided but that stud can be loosened and turned only part way around 80 to restore it to its original surface and when it is worn all around the stud can be removed and replaced at very little cost. The same is true of course of the plate 15 which has been described. 85

This invention is suitable for thread or yarn and I do not wish to be limited to either to the exclusion of the other.

Although I have illustrated and described only a single form of the invention I am aware of the fact that modifications can be made therein by any person skilled in the art without departing from the spirit and scope of the invention as expressed in the 90 claims. 95

Therefore I do not wish to be limited to the details of construction herein shown and described, but what I do claim is:—

1. The combination with a traverse frame and a guide holder movable along the frame, of a sheet metal bearing plate carried by the holder near the top at a point to engage the frame to receive the wear of the holder against the frame, said plate having integral side flanges detachably holding it on said holder. 100

2. A yarn guide for tubing or winding thread having two supports at its sides in the same plane arranged to contact with the yarn tube or package, two parallel walls extending backwardly from said supports, and being without any bottom support for the 110 yarn where it contacts with the tube or package.

3. A yarn guide for building up a yarn package by tubing or winding having two parallel studs, one constituting means for receiving the yarn, and the other means for guiding it to the package in a path tangent to the surface thereof throughout the entire operation of winding, and means for keeping said guiding means at a constant distance from the surface of the package as the latter increases in size. 115

4. A yarn guide for the purpose described comprising a stud for receiving the yarn and a pair of parallel side walls spaced about at right angles to the axis of the stud adapted to engage the yarn package, the 125 guide having no bottom bearing back of the 130

point discharge to deflect the yarn from a straight path from its support on the stud to the tube or package and thus permitting the yarn to have a path from the stud substantially tangent to the tube or package.

5. A yarn guide for the purpose described comprising a pair of parallel side walls spaced apart adapted to engage the yarn package, a bearing for the yarn between said 10 plates at a material distance back of the point of engagement with the yarn package, the guide having no bottom bearing back of the point of discharge to deflect the yarn from a straight path between said bearing 15 and the surface of the package, thus permitting the yarn to have a path tangent to the tube or package.

6. A yarn guide comprising two plates spaced apart to form a yarn receiving 20 groove between them, a yarn support extending across the space between the plates over which the yarn passes, said guide being adapted to press against the package being wound and said support being spaced from 25 the package, whereby the yarn will pass di-

rectly from the yarn support to the package and will not be deflected out of its straight path between them.

7. A yarn guide comprising two parallel plates spaced apart and having edge flanges 30 around them providing rounded corners for convenience in threading and constituting means for pressing against the package, and yarn support between the plates back of said flanges and constituting the sole means 35 for supporting the yarn between said plates.

8. As an article of manufacture, a yarn guide for the purpose described having no bottom bearing at the point at which the yarn contacts with the tube or package to deflect the thread or yarn from a straight path as it passes to the tube or package and having side supports bearing against the tube or package for insuring the spacing of the yarn in proper position during the 40 traverse motion.

In testimony whereof I have hereunto affixed my signature.

LEWIS T. HOUGHTON.
